HOOD FASTENER MECHANISM

Edward F. Reynolds, Flint, Mich., assignor to
 General Motors Corporation, Detroit, Mich., a
 corporation of Delaware

Application September 12, 1939, Serial No. 294,517

5 Claims. (Cl. 292—240)

This invention relates to hood latches and has particular reference to a latch for holding in lowered position the hood doors of automotive vehicles.

Due to the curving or streamlining of the extreme tip or nose of the hood, there has been a tendency for the tip of the hood doors to oscillate slightly when in closed position. This oscillation has been caused by the large part of the hood door between the forwardmost hood hinge and hood catch and the tip of the door, and in order to enable the curved tip of the hood door to be secured more firmly in position, an additional latch—adapted to engage and hold the tip of the door—has been provided as an auxiliary to the usual latching equipment. The additional catch comprises a crank arm placed on the end of the usual longitudinally mounted latch rod. A link secured to this crank arm operates a pivoted latch which engages under a catch secured to the underside of the hood door.

On the drawing

Figure 1 is a more or less perspective view of the hood of an automotive vehicle with the door in open position and showing the invention applied.

Figure 2 is a section through the structure of Figure 1 showing the invention applied, the hood door at the right being in latched position and the hood door at the left being unlatched and in open or partially raised position.

Figure 3 is a section on the line 3—3 of Figure 1.

Referring to the drawing, the numeral 2 indicates an automotive vehicle as a whole. The vehicle has the cowl 4, permanent hood side 6, the grille 8, and the hood doors 10. The hood doors 10 extend to the extreme forward end of the vehicle and each door terminates in a tip. The hood doors are hinged at their middle in the usual way and are capable of being moved on their hinges from the position shown at the right of Figure 2 to the position shown at the left of Figure 2. The hood side piece has the louver or decorative matter 12 at the front part on which a handle 14 is pivoted as at 16. In its closed position the handle 14 is flush with the hood side and with the louver 12. Beyond the pivot 16 the extension 18 has a link 20 secured thereto by the pin and slot connection 22. A spring 24 is secured to the extreme tip of the arm 18 and at its other end secured to the link 20. The spring always urges the handle 14 to a position in parallelism with the hood side 6. The other end of the link 20 is pivoted through the tension adjusting sector

plate 26 into a bar 28. The bar 28 is pivoted at 30 to an inner reinforcing plate 32 secured to the hood side 6. The sector plate 26 has three openings at its edge and in one of these openings the bent end 34 of a second link 36 is received. The end 34 also passes through a mating opening in the bar 28. The other end of the link 36 is secured to a crank 38 formed in a rod 40 mounted in bearings 42 at the upper edge of the hood side 6. The hood side is inturned as at 44 to form a more rigid construction.

At the cowl end of the rod 40 the crank arm 46 is provided and at the grille end a second crank 48 is provided and these cranks 46 and 48 engage under the flanged edge 50 on the hood door when the door is in lowered position. Preferably, brackets 52 are provided on the flanged edge 50 to receive the cranks 46 and 48.

The end of link 20 passing through the sector plate 26 forms the pivoting center for sector plate 26 when link 36 is assembled to the correct one of the three holes in the sector plate to acquire the correct tension between crank arms 46 and 48 and flanged edge 50.

At the grille end of rod 40 a third crank 54 is provided, and to this crank the link 56 is connected. The other end of the link is connected by an adjustable connection 57 to the lower end 58 of a latch arm 60 pivoted at 62 between the brackets 64 secured to the underside of the dome 66, positioned at the front of the vehicle under the hood and secured over the grille 8 and the radiator. The dome is provided with suitable openings 68 through which the upper or latch ends 70 of the latching arms 60 project. The ends 70 are provided with a head and adapted to engage a catch 80 formed on the end of a metal strip 82 secured to the underside of the hood door. The strip 82 extends the full width of the door and is secured at its lower end to the flange 50 as shown at 84, and at its upper end to the flange 85 on the door.

When the operator moves the handle 14 the parts will be moved from the full line position at the right of Figure 2 to the full line position to the left of Figure 2 and this movement will release the latch ends 70 as well as the cranks 46 and 48 to enable the hood door to be raised. When the door at the left of Figure 2 is lowered to the position shown at the right of Figure 2, the flange 50 will engage over or mate with the flange 44 and then by pushing the handle 14 from the position shown in Figure 1 inwardly, the crank arms 46 and 48 and the latch end 70 will

engage under their respective catches to hold the hood door in latched position.

I claim:

1. In a latching mechanism for the hinged hood door of an automotive vehicle, said door extending to the extreme forward end of the vehicle, a rod or shaft journally mounted on the vehicle adjacent the hood door, means to operate the shaft, means on the shaft to engage the hood door when in lowered position to latch the hood, and a separate latch operatively connected to and spaced from the shaft and capable of engaging the tip of the door when in lowered position tightly to hold the tip in latched position.

2. In a latching mechanism for the hinged hood door of an automotive vehicle, said door extending to the extreme forward end of the vehicle, means operatively to engage the edge of the door to hold the door in latched position, and a separate latch operatively connected to and simultaneously operative with the said means to engage the tip of the door tightly to hold the tip in latched position.

3. In a latching mechanism for the hinged hood door of an automotive vehicle, said door extending to the extreme forward end of the vehicle, means operative from the exterior of the hood for latching the edge of the door in lowered po-

sition, a crank on said means, a link connected to the crank, a pivoted latching element connected to the link, and a catch on the door adapted to be engaged by the latching element to retain the tip of the door in latched position.

4. In a latching mechanism for the hinged hood door of an automotive vehicle, said door extending to the extreme forward end of the vehicle, means operative from the exterior of the hood for latching the edge of the door in lowered position, a crank on said means, a link connected to the crank, a dome at the front of the vehicle and under the hood door, a latching element pivotally mounted on the dome and connected to the link, and a catch on the door adapted to be engaged by the latching element to retain the tip of the door in latched position.

5. In a means for latching the tip of the hood door of an automotive vehicle, said tip being downwardly and forwardly curved and extending to the extreme forward end of the vehicle, a mechanism extending longitudinally of the hood to latch the side of the door, a separate latching element operably connected to and spaced from said mechanism, and a catch on the tip engageable with said latching element to hold the tip in latched position.

EDWARD F. REYNOLDS.
